(57) **CLAIM**

The ornamental design for a film applicator, as shown and described.

DESCRIPTION

FIG. 1 is a front, right, and top perspective view of a film applicator showing my new design;
FIG. 2 is a rear, left, and bottom perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan view thereof;
FIG. 9 is an enlarged view of portion 9 shown in FIG. 1; and,
FIG. 10 is an exploded front, right, and top perspective view thereof.

The dash-dash broken lines in the drawings depict portions of the film applicator that form no part of the claimed design. The dot-dash broken lines in FIGS. 1 and 9 represent the boundaries of the enlarged portion and form no part of the claimed design.
